UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPGRAPHICAL MACHINE.

1,125,116.

Specification of Letters Patent. Patented Jan. 19, 1915.

Application filed March 6, 1913. Serial No. 752,261.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

My invention relates to typographical machines, such as linotype machines of the general organization represented in Letters Patent of the United States, No. 436,532, to O. Mergenthaler, wherein circulating matrices are released from a magazine or magazines in the order in which their characters are to appear in print and then assembled in line, the composed line transferred to the face of a mold, the mold filled with molten metal to form a slug or linotype against the matrices which produce the type characters thereon, and the matrices thereafter elevated and returned through a distributing mechanism to the magazine or magazines from which they started.

The present improvements relate more particularly to the font-distinguisher, which is employed to prevent matrices of different font from being delivered into a magazine designed for matrices of a particular font. Ordinarily, matrices of a given style or size have specially located font indicating notches, and the font-distinguisher has a projecting finger similarly located, to permit the passage of corresponding matrices and to arrest matrices formed with notches in a different position, all as well known in the art. In my U. S. Letters Patent No. 1,080,348, dated December 2, 1913, are illustrated connections whereby the distinguisher is automatically adjusted to correspond to the magazine in operative position, and my present improvement resides largely in the provision of additional means, whereby it may be shifted to an entirely inoperative position, when desired, the parts being adapted for either the manual or automatic adjustment of the distinguisher to that end.

Obviously many changes and variations may be made in the embodiment of the invention, and in its mode of application, which will still be comprised within its spirit; and generally speaking, I desire it to be understood that I do not limit myself

to any specific form or embodiment, except in so far as such limitations are specified in the claims.

Referring to the drawings: Figure 1 is a perspective view of a portion of a linotype machine of the character described, having my invention applied thereto; Fig. 2 is a side view, partly in section, showing the font distinguisher automatically shifted to inoperative position; Fig. 3 is a sectional detail on the line 3—3 in Fig. 2; Fig. 4 is a perspective of the disk shown in Figs. 2 and 3; Fig. 5 illustrates two matrices with different font notches; Fig. 6 is a view similar to Fig. 2, illustrating the manner in which the font distinguisher may be manually moved to inoperative position; and Fig. 7 is a sectional detail on the line 7—7 in Fig. 6.

Referring to Fig. 1, the magazines A¹, A², A³, are mounted in the shift frame A, and are also detachably arranged therein, substantially in the manner set forth in the U. S. Letters Patent of John R. Rogers, No. 1,109,872, dated September 8, 1914. The font-distinguisher B, provided with the projecting finger B¹ (see also Figs. 2 and 6), is located between the distributor box C and the other distributing devices, which latter comprise the lifting finger C¹, the screws D, and the inclined plates C⁵. The matrices X and X¹ are moved through the box C and presented to the lifting finger C¹, which finger delivers the matrices to the screws, etc., all in the customary manner.

The font-distinguisher B and its finger B¹ are adjustably mounted in the box C, immediately in advance of the lifting finger C¹, and in such position as to prevent the delivery of a matrix to the finger, unless the notch therein corresponds in position to that of the finger B¹. Fig. 5 shows two matrices X and X¹ of different fonts and formed with differently located notches Y and Y¹, it being apparent that if the finger B be set to register with the notches in one of these fonts of matrices, it will prevent the lateral passage of the other.

The distinguisher B is formed at one end with the button B³, between which and the box C is mounted the spring B², so as normally to hold the finger B¹ in its extreme left hand position. To effect the automatic adjustment of the distinguisher B and its finger B¹, to correspond to the particular

magazine in operative position, I employ the arm E^1 pivotally mounted at E in the main frame and provided with the extended arm E^2 beyond the pivot, the two arms 5 together constituting a lever. The arm E^2 is so shaped and located as to be in the path of the operating abutments G , mounted upon the piece F which is connected by the bracket A^{10} to the magazine frame A . As 10 the magazines are shifted to bring one or another of them into operative position, the corresponding abutment G acts upon the arm E^2 and varies the position of the arm E^1 , and through the contact of the latter with the button E^3 , the finger B^1 is 15 moved to register with the notches of the particular matrices in action. The parts so far described and their mode of operation are or may be similar to those described 20 in my previously mentioned Letters Patent, wherein also substantially the same letters of reference are employed.

It occasionally happens that it is desirable to shift the font-distinguisher entirely 25 out of action, that is to say, to remove the finger B^1 from the path of the matrices passing through the distributor box, for instance, when the operative magazine contains different fonts of matrices, or matrices 30 formed with differently located notches, as sometimes occurs in practice. To this end, I supplement the abutment G with a plate H , which may be brought into operation when necessary. The plate H is preferably 35 reversible and rotatable, and is formed with a part of its periphery projecting radially considerably beyond that of the abutment G . As shown in the drawings, it has a notch H^1 adapted to engage the stud F^1 , 40 which holds the abutment G in position, and is further provided with a projecting pin H^2 to engage one or another of two holes F^2 formed in the piece F . Due to this construction, the plate H may be readily applied, or reversed, and locked in place, 45 when desired.

Assuming the magazine A^1 to contain matrices of two different fonts, as for instance large capital letters for the main 50 head lines and smaller capital letters for the subhead lines, which matrices are formed with differently located font notches, it is obvious that both sets could not be transferred through the distributor 55 box unless the font-distinguisher be thrown entirely out of action. This result is readily obtained by employing the additional plate H , as best shown in Figs. 1 and 2, which projects beyond the ordinary abut- 60 ment G and shifts the lever E^2 , E^1 , to an extent sufficient to remove the finger B^1 entirely from the path of the matrices.

As previously stated, the plate H is rotatable about the stud F^1 and may be locked 65 in either operative or inoperative position,

the latter being indicated by dotted lines in Fig. 2. This capability permits the permanent application of both plates G and H to any given magazine. In ordinary circumstances, when the plate H is turned 70 and held in inoperative position, the plate G will control the adjusting lever arm, as set forth in my previous application; but when turned to operative position, and due to its greater radial dimensions, it will act 75 upon the lever arm and render the font-distinguisher inoperative, in the manner previously described. Of course, the plate H may be employed alone, when for any reason it be desired to render the font-distinguisher inactive. 80

Another feature of my invention is the construction of the parts in such manner that the font-distinguisher may be also manually locked out of action, which feature is best illustrated in Figs. 6 and 7. To this end, the recess C^1 in the side of the box C , through which the font-distinguisher B projects, is shaped to correspond to the form of the finger B^1 . Therefore, if the 90 distinguisher and its finger be shifted therethrough, as shown in Fig. 6, and then turned about its axis, as indicated in Fig. 7, the distinguisher will be locked and held in inoperative position by the engagement of the 95 finger with the side of the box. This capability permits the permanent locking of the parts out of action, without reliance upon the automatic means above set forth.

As previously stated, my invention is 100 shown only in preferred form and by way of example, and as applied to a specific type of machine, but obviously many modifications and variations therein, and in its mode of application, will suggest them- 105 selves to those skilled in the art without departure from its scope.

Having thus described my invention, its construction and mode of operation, what I claim and desire to secure by Letters Patent 110 of the United States, is as follows:—

1. In a typographical machine, the combination of a channel through which the type or matrices travel, and a font distinguisher located in said channel and movable laterally thereof out of the path of travel of the type or matrices, for the purpose described. 115

2. In a typographical machine, the combination of a channel through which the type or matrices travel, a movable font distinguisher located in said channel, a spring acting to maintain the font distinguisher in the path of travel of the matrices, and means for holding said distinguisher out of 125 the path of travel of the matrices against the action of the spring.

3. In a typographical machine, the combination of a font-distinguisher movable to different operative positions, and means for 130

automatically moving it to an inoperative position, when required.

4. In a typographical machine, the combination of a plurality of magazines, a font-distinguisher movable to different operative positions to correspond to one or another of the magazines, and means for automatically moving it to an inoperative position when a given magazine is brought into action.

10 5. In a typographical machine, the combination of a magazine, a font-distinguisher movable to different operative positions to correspond to different styles or fonts of type or matrices therein, and means for automatically moving it to an inoperative position when required.

6. In a typographical machine, the combination of a plurality of magazines, a font-distinguisher, and mechanism for adjusting it to different operative positions to correspond to the magazine in action, the said adjusting mechanism comprising means for moving the font-distinguisher to an inoperative position when a given magazine is brought into action.

7. In a typographical machine, the combination of a plurality of magazines, a font-distinguisher, and mechanism for automatically adjusting it to different operative positions to correspond to the magazine in action, the said adjusting mechanism comprising means shiftable at will to cause the distinguisher to be moved to an inoperative position when a given magazine is brought into action.

8. In a typographical machine, the combination of a magazine adapted to be brought into action at will, an adjustable font distinguisher, and mechanism for automatically adjusting it, the said mechanism comprising means shiftable at will to cause the font distinguisher to be adjusted automatically either to an operative or an inoperative position when said magazine is brought into action.

45 9. In a typographical machine, the com-

bination of a plurality of magazines, one or another of which can be brought into action at will, a font-distinguisher, and mechanism for automatically adjusting it to correspond to the magazine in action, the said adjusting mechanism comprising means to cause the font-distinguisher to be adjusted to an operative or inoperative position as desired when any given magazine is brought into action.

10 10. In a typographical machine, the combination of a plurality of magazines, one or another of which can be brought into action at will, a font-distinguisher, and mechanism for automatically adjusting it to correspond to the magazine in action, the said adjusting mechanism comprising means that may be shifted at will to cause the distinguisher to be adjusted to an operative or inoperative position as desired when any given magazine is brought into action.

11. In a typographical machine, the combination of a font-distinguisher, and mechanism for adjusting it, the said adjusting mechanism comprising means to vary the extent of adjustment of the font distinguisher to correspond to different styles of type or matrices and further means to render it inactive when required.

12. In a typographical machine, the combination of a magazine adapted to be brought into action at will, an adjustable font distinguisher, and means for adjusting it, the said means including an element shiftable at will to vary the extent of action of said means so as to cause the font distinguisher to be adjusted to an active or inactive position as desired when said magazine is brought into action.

85 In testimony whereof I have affixed my signature in presence of two witnesses.
